AIR CONDITIONER

Clarke Redfield, Tenafly, N. J.

Application July 30, 1934, Serial No. 737,537

10 Claims. (Cl. 62—135)

The purpose of this invention is to provide means for conditioning air by refrigeration and also to circulate the air thru all parts of a room or enclosure.

5 The invention is a cooling unit adapted to be supported from the ceiling of a room or enclosure, similar to a light fixture, or from the floor, and comprises a plurality of extended surfaces with a refrigerant associated therewith and with 10 air circulating means adapted to radially discharge air therefrom.

Air conditioning devices of this type generally comprise a fan and a cooling unit, but the fan generally blows air over the unit, and it is discharged in a comparatively straight stream, so that it is not circulated around the room or enclosure, and generally requires additional means to obtain efficient circulation.

15 The object of this invention is, therefore, to provide a refrigerating unit in combination with a fan, in which the fan draws air thru the unit and discharges it in a circular stream, thereby distributing it thruout a room or enclosure in which it may be installed.

20 Another object is to provide a cooling unit having a plurality of circular fins thru which a refrigerant may be passed by pipe coils, with means for drawing air into the center and discharging it thruout the periphery thereof.

25 A further object is to provide an air conditioning unit having circular fins with means discharging air thruout a complete circle, which may be supported from the ceiling or from the floor in a room or enclosure.

30 And a still further object is to provide an air conditioning unit in combination with air circulating means thru said unit and thruout a room or enclosure which is of a simple and economical construction.

35 With these ends in view the invention embodies a plurality of extended surfaces, a refrigerant pipe coil extending thru said surfaces, a fan adapted to be rotated around said surfaces, a drip pan with a pump for discharging condensate, and motive power adapted to operate said fan.

40 Other features and advantages of the invention will appear for mthe following description, taken in connection with the drawings, wherein:

45 Figure 1 is a view showing a room or enclosure with the device positioned therein.

50 Figure 2 is a view showing a side elevation of the device with part broken away.

55 Figure 3 is a plan view with parts omitted and with parts broken away, showing a portion of the

top of the casing, portion of the fins with the pipe coils running therethru, and a portion of the bottom plate or spider upon which the fan blades are supported.

Figure 4 is a view showing an alternate design in which the air circulating means is operated by the latent energy of the refrigerant, and the device is inverted, showing it as it may be used on a pedestal, three quarter partition, or the like.

In the Figures 1, 2 and 3 the device is shown 10 as it may be made wherein numeral 1 indicates the fins, numeral 2 the fan blades, and numeral 3 the condensate pump.

The fins 1 are indicated by single lines as they are comparatively thin, and these may be curved, 15 straight or corrugated, or reinforced in any manner; and they may also be provided with openings other than the pipe coil openings thru which condensate may pass to the drip pan.

The fins 1 are preferably made of comparatively thin sheet metal of a circular shape and with gradually enlarging circular openings at their centers forming an opening 4 in the center, similar to the frustum of a cone. In the design shown these fins are circular, however, it will be 25 understood that they may be made of any shape and an opening of any design may be provided in the center. These fins are provided with a plurality of openings 5 thru which a continuous

20 pipe coil 6 extends, as shown in Figures 2 and 3, 30 and one end of this coil is connected to an expansion valve 7 which is connected to a supply pipe 8, and the other end 9 of the coil extends upward thru a base 10 of the device, and this end may be connected to any suitable return or 35 exhaust. The pipe coil 6 may be passed thru the fins in any manner, and may be provided with any connections to facilitate the construction.

It is understood that a typical coil is shown in the drawings with all fittings and connections omitted. This coil is supported by 40 brackets 11 from a cover plate 12, and the cover plate is secured to a continuous flange 13 on arms 14 extending from the base 10 by bolts 15, and it will be noted that with the bracket consisting 45

of the base 10 and arms 14 held to a ceiling, or the like, by bolts 16, the unit supported by the brackets 11 with the cover 12 may be placed over the lower part of the bracket and up against the flange 13, to which it may be secured by the bolts 50

15. It will be understood, however, that the unit and cover plate may be attached to the cover or base by any other means. The fan blades 2 are positioned around the fins 1, and these are mounted upon a plate or spider 17, 55

which is mounted upon a hub 18 at the lower end of a spindle 19 extending downward from a motor 20, with the lower end of the spindle held in a bearing 21 at the lower end of the arms 14, and 5 it will be noted that as the motor rotates, the blades 2 will be rotated about the fins 1 thru the member 17 and, with the blades correctly positioned, a current of air will be drawn thru the fins and discharged in the direction of the arrows 10 22, thereby discharging the air about the periphery of the device and forming a continuous circular stream which will circulate thruout a room or enclosure in which the device may be installed, as indicated by the arrows shown in Figure 1.

15 In the design shown, a motor 20 is attached to the base 10 and in this arrangement it is suspended from the base, however, it will be understood that any means may be provided for mounting the motor, and this may be attached to the 20 base or any part thereof, or suspended in any manner.

Below the fins 1 and coil 6 is a drip pan 23, which may be attached to the coil by clips 24, or by any means, and it will be noted that this pan 25 slopes downward toward a trough 25 at the center, and this trough is connected to the pump 3 on the motor spindle 19 thru a connection 26. The pump 3 is provided with a discharge connection 27 that extends upward thru the base 10, and this 30 may extend to any point from which the drip or condensate may be discharged. The drip pan is positioned under the coil and fins so that moisture condensed from the air passing thru the fins will accumulate in this pan and will be discharged to a remote point. It will be understood 35 that any other means may be used for taking care of this condensate, and it may be conveyed to a remote point by any means.

The fan blades 2 are preferably made straight, 40 as shown in Figure 3, however, these may be made of any shape, and any means may be provided for mounting them on the lower end of a motor spindle. The motor may also be positioned at any other point and may be connected 45 to the blades by any means. The member 17 is shown in a conical shape, however, it will be noted that this may be flat, curved, or formed in any manner. The fan blades are mounted 50 on the outer edge thereof and may be soldered in place, or attached thereto or made integral therewith, as may be desired. It is preferred to use a ring 28 connecting the upper ends of the blades, however, it will be understood that this 55 may be omitted, or the blades may be connected or held by any means.

In the design shown in Figure 4 the device is 60 shown as it may be used on a pedestal, stand or three-quarter partition, and in which the motor is omitted and the fan operated by an engine 29, operated by the latent energy of the refrigerant. In this design the engine 29 is supported upon a stand 30 having a base 31 that may rest upon the upper end of a pedestal or stand 32, or on a partition of the type that terminates short of 65 the ceiling, however, it will be understood that the stand 30 may be of any type or design, may be supported in any manner, and the engine 29 may be supported from a hanging bracket similar to that shown in Figure 2, or in any manner. 70 In this design the spider 17 is replaced by a continuous plate 33 forming a cover, with fan blades 34, similar to the blades 2, extending downward therefrom, and the lower ends of the blades are connected by a continuous ring 35, or by any 75 means. The member 33 is supported on the up-

per end of a shaft 36 extending upward from the engine 29, and it will be noted that this will be rotated by the engine. A shell 37 forming the base also forms a drip pan below the device with a circular trough 38 extending around the inner part thereof, and this may be provided with a connection 39, which will convey the drip to any point desired by gravity. This connection may, however, be connected to any means for disposing of the drip or condensate, or for pumping the 10 drip or condensate to any point.

In this design the horizontal fins 1 are replaced by vertically positioned plates 30, and the coil 6 is replaced by a coil 41, which extends thru the plates, as shown. The upper or supply end 15 of the coil is connected to the exhaust of the engine 29 by a pipe 42, and the lower or suction end of a coil is connected by a pipe 43 to the suction line of a compressor or to any means for withdrawing the refrigerant. The refrigerant 20 may be supplied thru a pipe 44, which is connected to the engine 29, and it will be noted that the engine may be of any type or design, or any combination of mechanical devices may be provided for utilizing the latent energy of the refrigerant and converting it into work producing means for operating the air circulating means. Air may be drawn in thru the lower part of the stand below the base 37 as indicated by the arrows and this may be covered with a grille or 30 screen 45, which may be of any type. The air will be drawn thru the plates and radially discharged thruout the periphery of the unit, thereby circulating the air in the same manner as in the design shown in Figure 2.

35 It will be understood that other changes may be made in the construction without departing from the spirit of the invention. One of which changes may be in the use of other means for applying a refrigerant to the fins, another may 40 be in the use of a fan of any other type, and still another may be in the use of other means for mounting a fan in relation to the cooling unit.

45 It will be understood that any refrigerant may be circulated thru the coils to produce the refrigerating effect. Some common refrigerants which may be used are methyl chloride, sulphur dioxide, carbon dioxide, Freon or any other gas used as a refrigerant or any other medium which at any time may be introduced into the industry. 50 It will be understood that a refrigerated brine may be used by the omission of the expansion valve. This brine may be a solution of sodium chloride, glycerine, alcohol or any other brine found desirable, or sweet water, refrigerated in 55 any way. The use of the term "refrigerant" is understood to mean any refrigerating medium.

It will also be understood that the device may be used as independently as a fan to circulate air in a room or enclosure, without having the 60 refrigerant pass thru the coils when cooling is not desired.

The construction will readily be understood from the foregoing description. In use the device may be provided as a complete unit and 65 installed by attaching the base 10 or the base 31 to the ceiling of a room, or to any device from the floor, or to any member or part of a room or enclosure which will permit a comparatively free circulation of air from the device around the 70 room. In the design, as shown in Figure 2, the refrigerating fluid inlet and outlet pipes and the condensate pipe, as well as the electrical connection for the motor extend upward thru the base, and these may extend to any point or may be 75

connected to any means for supplying the fluid or taking care of the discharge or exhaust. The electrical connection for the motor may also extend to a wall switch and to any source of supply 5 of electric current.

The device may be mounted on the base and the base attached to the ceiling or other surface, and it will be noted that similar devices may be placed in different rooms in a building and all 10 connected to a common switch board, or each may be provided with independent connections so that each may be turned on or off, as may be desired. It will be noted that when the motor is started and with a refrigerating fluid passing 15 thru the coil, the temperature of the fins will be reduced materially and these, in turn, will extract heat units from air passing therethru, so that the air will give up its heat and the temperature thereof will be materially reduced. This 20 device draws air in thru the center, preferably from the lower side, and this air, after being cooled, is discharged around the periphery and, as the fan will impart considerable velocity thereto, this air will continue to circulate around a 25 room, as shown in Figure 1, and as it passes by windows or exterior openings, it would draw air in from the outside, thereby maintaining a continuous supply of fresh air with complete circulation. Discharging air outward from a central 30 point adjacent the ceiling of a room or enclosure creates ideal circulation, as the air passes outward in every direction, and down the walls, and is drawn up again to the center of the room or enclosure, thereby keeping all air in the room in 35 complete circulation at all times.

Having thus fully described the invention, what I claim as new and desire to secure by Letters Patent, is:

1. An air conditioner comprising a cooling 40 means including superposed annular fins having a centrally disposed air intake opening, a plurality of circumferentially arranged fan blades extending outwardly of the peripheral edges of said fins for drawing air through said fins and past said cooling means and forcing air outwardly in a plane coplanar with said fins, and operating means for said blades.

2. An air conditioner comprising a cooling coil, a plurality of superposed annular fins having a 50 centrally disposed air intake opening, said coil being threaded through said fins about said opening, and means for drawing air through said intake opening and past said coil in a plane coplanar with the sides of said fins.

3. An air conditioner comprising a cooling 55 means including superposed annular fins having a centrally disposed air intake opening, a plurality of circumferentially arranged fan blades extending outwardly of the peripheral edges of said fins for drawing air through said fins and past said cooling means and forcing air outwardly of said fins and in alinement with the opposite faces thereof, a centrally disposed operating means for said blades, and a web connecting said 60 operating means with said blades.

4. An air conditioner comprising a cooling

means including superposed annular fins having a centrally disposed air intake opening, a plurality of circumferentially arranged fan blades extending outwardly of the peripheral edges of said fins for drawing air through said fins and past said cooling means and forcing air outwardly of said fins and in alinement with the opposite faces thereof, a centrally disposed operating means for said blades, a web connecting said operating means with said blades, and means disposed below said fins for collecting condensate. 5

5. An air conditioner comprising a cooling means including superposed annular fins having a centrally disposed air intake opening, a plurality of circumferentially arranged fan blades 15 extending outwardly of the peripheral edges of said fins for drawing air through said fins, a centrally disposed operating means for said blades, a web below said fins connecting said operating means with said blades, and means disposed between said web and said fins for collecting condensate. 20

6. An air conditioner comprising a cooling means including superposed annular fins having a centrally disposed air intake opening, a plurality of circumferentially arranged fan blades 25 extending outwardly of the peripheral edges of said fins for drawing air through said fins, an operating means for said blades, a web below said fins connecting said operating means with said blades, 30 a condensate collecting pan disposed between said web and said fins, and means for supporting said pan from said cooling means.

7. An air conditioner comprising a cooling coil, a plurality of superposed annular fins having a 35 centrally disposed air intake opening, said coil being threaded back and forth through said fins, and means for drawing air through said intake opening and past said coil and discharging the air radially in all directions about the periphery 40 of said fins.

8. An air conditioner comprising a plurality of superposed annular fins having a centrally disposed air intake opening, a cooling coil threaded back and forth through said fins about said opening, means for forcing air through said opening between said fins, and means for collecting the condensate from said fins. 45

9. An air conditioner comprising a plurality of fins disposed in spaced apart relation, a cooling 50 coil threaded back and forth through said fins, said fins having axially aligned air openings, and means for drawing air through said openings and in the space between the fins and discharging the air outwardly of the marginal edges of the 55 fins.

10. An air conditioner comprising a cooling means including a plurality of spaced apart fins having a centrally disposed air intake opening, a plurality of fan blades arranged at the marginal 60 edges of the fins for drawing air through said fins and past said cooling means and forcing air outwardly in a plane coplanar with said fins, and operating means for said blades. 65
